UNITED STATES PATENT OFFICE

NORMAN M. FRASER, OF NORWALK, OHIO.

ATTACHMENT FOR OIL-WELLS.

1,017,663.

Specification of Letters Patent. Patented Feb. 20, 1912.

Application filed June 20, 1910. Serial No. 567,947.

To all whom it may concern:

Be it known that I, NORMAN M. FRASER, a citizen of the United States of America, and resident of Norwalk, in the county of Huron and State of Ohio, have invented certain new and useful Improvements in Attachments for Oil-WellS, of which the following is a specification.

This invention relates to apparatus for pumping oil and particularly to a device designed for the purpose of saving oil at the top of a well, the said apparatus being designed to be used in connection with the cable of a pump.

15 An object of this invention is to produce a device capable of being applied to or installed with pumps which are already in operation or they may be used in connection with pumps which are being erected.

20 A further object of this invention is to produce a device comprising detachably connected parts which may be assembled or built around a piston rod in conjunction with the casing head, whereby the cable is permitted to move therethrough and whereby oil is prevented from discharging around the cable or through the oil guarding means.

25 With the foregoing and other objects in view, the invention consists in the details of construction and in the arrangement and combination of parts to be hereinafter more fully set forth and claimed.

30 In describing the invention in detail, reference will be had to the accompanying drawings forming part of this specification wherein like characters denote corresponding parts in the several views, in which—

35 Figure 1 illustrates a view in elevation of the oil well attachment embodying the invention; Fig. 2 illustrates a transverse sectional view; Fig. 3 illustrates a perspective view of a cap; Fig. 4 illustrates a detail view of the sections of the body; Fig. 5 illustrates a perspective view of the sections 40 of packing; and Fig. 6 illustrates a perspective view of the sections of a washer.

45 In these drawings 7 and 8 denote the sections of the body each of which is provided with ears 9, 9 and 10, 10 respectively apertured to receive the bolts or other fastenings 11 by which they are bound together. Each section has a recessed inner wall, the recesses of the two walls coinciding to form an annular channel for the reception of a washer 12 50 comprising two semi-circular sections, a packing 13 and a large washer 14 also com-

55 prising two semi-circular sections. At the bottom of each section 7 and 8, there is a shoulder 15 and 16 respectively which shoulders have recesses in their edges forming a channel for the passage therethrough of the cable 17.

60 Exteriorly, the sections 7 and 8 are screw threaded near the top and a cap 18 is threaded on the said sections and is adapted to bear against the washer 14 for the purpose of pressing it against the packing. By this means, the pressure on the packing may be increased or diminished in order to effect a tight joint and prevent the escape of oil 65 between the cable and the packing. The cap is provided with a radial slot 19 which extends throughout the axial length of the cap and which terminates at a point beyond its axis; and the inner terminus thereof constitutes an aperture through which the piston reciprocates. The slot 19 provides a quick, easy and convenient channel through which the cap is applied to the body. By reason of the fact that all the parts of the attachment are made in sections, except the cap, the said device may be assembled 70 around a cable and when they have been secured together in the usual way, the sections 7 and 8 may be anchored to the casing 75 head by means of spikes or the like (not shown) as any appropriate fastenings may be adopted for the purpose of anchoring the body.

80 It is the purpose of the inventor to construct washers 12 and 14 of hard steel in order that they will withstand the wear incident to the movement of the cable through them and as these washers are the only parts of the attachment which can wear away to 85 an extent to impair the utility of the device, these washers are readily removable. By reason of the construction indicated, therefore, the durability of the attachment is increased as compared with devices now in 90 general use and owing to the fact that these washers may be readily removed and replaced, the cost of maintenance is minimized.

95 I claim—

100 1. A piston guide and packing comprising two semi-cylindrical sections each having an aperture therein and each having a shoulder at the terminus of the aperture and each having an externally screw threaded end, metal washers fitted into the apertures 105 through which the piston extends, packing

material around the piston and between the washers, and an internally screw-threaded cap fitted onto the external screw threads of the semi-cylindrical members, said cap having a radial slot extending throughout the axial length thereof and terminating in a central aperture through which the piston extends.

2. A piston guide and packing comprising semi-cylindrical apertured members secured together with said apertures adjacent to each other and having a piston extending therebetween, packing material in the aper-

tures around the piston, and a cap screw threaded onto the semi-cylindrical members, 15 said cap having a radial slot extending throughout the axial length thereof and extending radially inward beyond the center and terminating in an aperture through which the piston extends. 20

In testimony whereof, I affix my signature in the presence of two witnesses.

NORMAN M. FRASER.
